BOWLING BALL

Frank M. Darby, Chicago, Ill.

Application March 16, 1940, Serial No. 324,273

5 Claims. (Cl. 273—63)

My invention relates to playing balls and particularly to bowling balls of the type adapted for use in playing ten pins.

Balls of this character are provided with two or more radial openings, one for the thumb and one, or in some cases two, for the fingers. While little attention is paid to the size of the openings for the fingers, the diameter of the opening for the thumb is of great importance. The fit should be such that the thumb may move smoothly in and out; that is to say, exactly the right frictional resistance should be provided and this can be changed by very slight variations in the effective diameter of the thumb hole.

This required accuracy of fit results in difficulties in use, due to expansion and contraction of the solid material of the ball, the humidity of the surrounding air, as reflected in perspiration, and other features, all of which makes it desirable to provide for relatively slight variations in the effective diameter of the opening.

To that end I have provided very simple means adapted for operation by a flat tool, such as a screw driver, whereby adjustments may be effected within the space of a few seconds in order to compensate for changes in the described conditions.

The mechanism adapted to function in the described manner is illustrated in the accompanying drawing; in which,

Fig. 1 is a fragmentary sectional view through a bowling ball, showing my improvement applied thereto;

Fig. 2 is a similar view in elevation;

Fig. 3 is an upper end view of the sleeve shown in Figs. 1 and 2; and,

Fig. 4 is a similar view of a sleeve having slots arranged in a slightly different manner.

A bowling ball is indicated at 10, usually composed of a hard and dense composition material. A radial opening is bored in the ball, the opening, as shown in Fig. 1 having three diameters 11, 12, and 13. In the outer portion 13 of the opening I seat a thimble 14, preferably located permanently in place, since the size of the outer portion of the thumb hole is not of great importance. It will be understood, of course, that the effective size of this portion may be varied by replacing the thimble with one of a different size.

The intermediate portion 12 of the opening receives a sleeve or tube 15, composed of somewhat resilient material, the upper portion of which is provided with numerous slits 16 extending longitudinally inward from the open end of the tube

for a short distance. The lower end of the tube is closed by a transverse wall 17 having an opening to receive the shank of a screw 18. Means such as the washer and pin 19 may be employed for anchoring the screw against longitudinal movement, but permitting its rotation. A threaded portion 20 of the screw engages a threaded nut 21 permanently held in the narrow portion 11 of the opening. It will be seen that by rotating the screw the sleeve may be moved up or down as desired.

The space intervening between the portions 12—13 of the opening is inclined, as indicated at 22, and the upper end of the sleeve is flared, as at 23, to correspond to the incline of the 15 wall. Thus the sleeve is forced downward by actuating the screw, the effective diameter of the opening where it engages the knuckle of the thumb may be lessened to a desired extent. In Figs. 1 and 2 the sleeve is shown at its upper 20 limit; that is at the point of greatest diameter of the sleeve.

In the construction of Fig. 2 the screw 20 directly engages a threaded opening 22a in the material of the ball, rather than a nut seated 25 in the body of the ball.

In the construction of Figs. 1, 2 and 3, the slots 16 are arranged radially of the sleeve. As shown in Fig. 4 I may prefer to arrange the slots 16a at a tangent and to round the inner corners, 30 thereby lessening possible damage to the skin on the knuckle of the user.

Apparatus such as described is entirely concealed within the body of the ball and thus cannot be damaged in use. By the use of sleeves 35 of different diameters a wide range of thumb-hole diameters may be provided, thus enabling the manufacturer to provide all balls with a standard size opening. However, the most important advantage is to the user, who may vary 40 the size of the thumb-hole as occasion requires.

It is obvious the same result may be secured by boring the ball opening of uniform diameter from end to end, then fixing therein a unit having the sleeve and inclined surfaces for varying the 45 diameter of the sleeve in the manner described. This and other modifications are considered to be within the scope of my invention.

I claim:

1. A bowling ball having a radially arranged¹ opening, the diameter of the inner portion of the opening being less than that of the outer portion, the portions of different diameters being joined by an inclined area, a slotted sleeve in the smaller portion of the opening and having a 55

- tapered portion engaging said inclined area, and means for positively moving said sleeve axially of the opening whereby to vary the diameter of the sleeve, due to sliding cooperation between the 5 inclined surfaces on the sleeve and the ball.
2. A bowling ball having a radially arranged opening, the diameter of the inner portion of the opening being less than that of the outer portion, the portions of different diameters being joined by an inclined area, a slotted sleeve 10 in the smaller portion of the opening and having a tapered portion engaging said inclined area, a thimble fixed in the outer end of the outer portion of the opening, and means for positively 15 moving said sleeve axially of the opening whereby to vary the diameter of the sleeve, due to sliding cooperation between the inclined surfaces on the sleeve and the ball.
3. A bowling ball having an opening of larger 20 diameter at its outer end than intended for use, and an inner portion of smaller diameter than the outer portion and also larger than intended for use, the two diameters being joined by an inclined portion, a slotted resilient sleeve seated 25 in the inner portion of the opening and having a tapered portion for engagement with said inclined portion, screw means operating at the inner extremity of the opening for effecting axial movement of the sleeve and consequent expansion and contraction of the effective diameter of 30 the sleeve.
4. A bowling ball having an opening of larger diameter at its outer end than intended for use, and an inner portion of smaller diameter than the outer portion and also larger than intended for use, the two diameters being joined by an 5 inclined portion, a slotted, resilient sleeve seated in the inner portion of the opening and having a tapered portion for engagement with said inclined portion, screw means for operating at the inner extremity of the opening for effecting axial 10 movement of the sleeve and consequent expansion and contraction of the effective diameter of the sleeve, and a thimble for contracting the diameter of the outer portion of the opening. 15
5. A bowling ball having an opening of larger diameter at its outer end than intended for use, and an inner portion of smaller diameter than the outer portion and also larger than intended for use, the two diameters being joined by an 20 inclined portion, a slotted, resilient sleeve seated in the inner portion of the opening and having a tapered portion for engagement with said inclined portion, screw means operating at the inner extremity of the opening for effecting axial 25 movement of the sleeve and consequent expansion and contraction of the effective diameter of the sleeve, and a thimble independent of the sleeve and fixed in the outer portion of the opening, and immovable relative to the movement of 30 the sleeve.
